UNITED STATES PATENT OFFICE.

JOHN WILLIAM PAYNE, OF ALEXANDRIA BAY, NEW YORK.

BICYCLE.

SPECIFICATION forming part of Letters Patent No. 642,560, dated January 30, 1900.

Application filed April 1, 1897. Serial No. 630,289. (No model.)

To all whom it may concern:

Be it known that I, JOHN WILLIAM PAYNE, a citizen of the United States, residing at Alexandria Bay, in the county of Jefferson and 5 State of New York, have invented a new and useful Bicycle, of which the following is a specification.

This invention relates to improvements in the general construction of the frame and adjunctive parts of safety-bicycles and tandems for juveniles, ladies, and gentlemen. A vital feature of the improvement is to enable wood to be successfully used in the construction of the frame and to obviate joints, which are the 10 chief source of trouble heretofore experienced in the employment of wood in the formation of frames for this class of machines. In accordance with this invention a rod or bar of wood of proper length is bent intermediate 15 of its ends into the required form by any of the known processes, and the extremities of the blank are secured to the branches of a plate forming a bearing for the axle of the rear or drive wheel. This rod or bar is split 20 and spread at proper points to afford clearance for the drive-wheel, the seat-post, and the steering-head and is strengthened and reinforced at such points as are spread and separated by suitable couplings, which in their 25 particular construction and relation constitute an important factor of the invention.

For a full understanding of the merits and advantages of the invention reference is to be had to the accompanying drawings and 30 the following description.

The improvement is susceptible of various changes in the form, proportion, and the minor details of construction without departing from the principle or sacrificing any of the 35 advantages thereof, and to a full disclosure of the invention an adaptation thereof is shown in the accompanying drawings, in which—

Figure 1 is an elevation of a frame for safety-bicycles especially designed for ladies and misses. Fig. 2 is a view similar to Fig. 45 1, showing a frame constructed in accordance with this invention particularly designed for men and boys. Fig. 3 is a side elevation of a combination-frame for ladies and gentlemen. Fig. 4 is a detail view of the rear fork, the upper portion being broken away and the joint formed between the fork

members and the top reach. Fig. 5 is a plan view of the wedge secured in the angle formed between the fork members. Fig. 6 is a front 55 view of the seat-post tube. Fig. 7 is a detail view in perspective of the clamp-ring for securing the seat-post within its tube at an adjusted position. Fig. 8 is a detail view in longitudinal section, showing the parts assembled of that portion of the frame located at the juncture of the top reach, rear fork, and brace. Fig. 9 is a side view of the coupling for connecting the upper end of the brace with the frame at the juncture of the top 60 reach and rear fork. Fig. 10 is a view in elevation of the forked plate to which the ends of the rod or bar constituting the frame are coupled. Fig. 11 is a detail view of the lower portion of the brace, showing the means for 65 connecting its fork members with the crank-hanger. Fig. 12 is a side view of the parts illustrated in Fig. 11. Fig. 13 shows the means for reinforcing the brace at the origin of the cleft. Fig. 14 is a detail view, partly 70 in section, showing the means for connecting a lady's or a miss's seat-post to the upright portion of the drop-frame. Fig. 15 is a detail view showing the reinforcing means for 75 strengthening the frame where it is spread for the passage therethrough of the steering-head. Fig. 16 is a plan view of the wedge or block secured between the separated parts of the frame. Fig. 17 is a detail view of the upper portion of the steering-head, showing the 80 means for connecting it with the frame. Fig. 18 is a group of the connections between the frame and upper portion of the steering-head.

Corresponding and like parts are referred to in the following description and indicated 85 in the several views of the accompanying drawings by the same reference characters.

In every instance the frame is constructed of a single strip or blank of wood having its end portions brought together and having the 90 intermediate portion bent into the required shape, according to the style of the machine and pattern of frame. The extremities of the wooden strip are secured to the forked members of a plate 1, which is located at the lower 95 rear end of the frame and forms a support for the axle of the rear or drive wheel. As shown in Fig. 4, the end portions of the blank or wooden strip are split and spread to afford 100

clearance for the rear wheel, and the fork members 2 are fitted against the branching members of the plate 1 and are secured in place by a cuff or sleeve 3, fitted thereon and 5 embracing the two. A shoulder 4 of each plate engages with the extremity of a fork and limits the upward or forward movement of the plate, as clearly indicated in Fig. 4. In order to prevent slipping, a series of points 5 10 project from a side of the plates and enter the forks 2, and in order to retain the sleeves 3 against accidental displacement interlocking teeth or serrations 6 are formed between the meeting faces of the plate 1 and the parts 3. 15 The serrations or teeth 6 incline toward the extremities of the forks 2, so as to admit of the sleeves 3 being forced to place and prevented from backward movement by the interlocking of the teeth, the latter riding over 20 each other when forcing the sleeves home and interlocking to prevent the backward movement of the sleeves, even though the parts 2 should shrink and cause a slight loosening. The sleeves are cut away on their inner sides 25 and front and rear edges, forming, in effect, bands, and the toothed or roughened portions of these bands are inclined, and the corresponding toothed portions of the plate 1 are correspondingly inclined, whereby a wedging 30 action is had to draw the parts 1 and 2 together when forcing the sleeves or cuffs home, as will be readily understood. The uprights or braces 7 and 8 have their lower portions spread similar to the rear fork and connected 35 with the crank-hanger 9 in precisely the same manner as the fork members 2, like reference characters denoting corresponding parts.

The crank-hanger 9, in addition to the branching or converging extensions, is formed 40 with a bearing-sleeve 10 and split collars 11, the latter being disposed at right angles to the bearing-sleeve and in a higher plane, so as to admit of the passage therethrough of the rod or strip comprising the machine-frame. 45 These split collars 11 have their end portions made tapering to receive rings 12, which are externally threaded to receive internally-threaded rings 13, by means of which the separated portions of the collars 11 are drawn 50 together and caused to grip the frame-bar. The rings 12 are notched to admit of their compression when turning up the rings 13 thereon. It is not absolutely necessary that the rings 12 be provided, as the tapering 55 extremities of the split collars may be externally threaded to receive the rings 13, thereby attaining the same end. At the inner end of the cleft is located a fastening similar to that applied to the extremities of the split collars 60 65 11 and consisting of correspondingly-threaded rings 12 and 13. The upper end of the brace 7 has a bore, in which is fitted the lower end of the seat-post tube 14, which is externally threaded and screwed into the said bore and 65 is provided with a ring 15 to obtain a bearing upon the end of the brace 7, thereby securing the tube in place against longitudinal

displacement. The upper end of the tube 14 is threaded and split and receives a ring 16 and a clamp-nut 17, the latter drawing the 70 separated portions of the tube together and clamping the seat-post 18 in an adjusted position.

The rear portion of the top reach 19 and the upper portion of the rear fork 20 are split and curved, and the separated portions receive 75 between them a wedge-shaped block 21, which curves longitudinally, corresponding with the curvature of the parts 19 and 20 opposite the brace 7. Plates 22 and 23 of wedge form are 80 applied to the top and bottom sides of the frame-bars opposite the block 21 and are secured together by bolts 24, which pass through corresponding openings in the plates and block. Ferrules 25 are forced over the 85 extremities of the plates 22 and 23 and secure them to the frame. The upper portion of the seat-post tube 14 passes through registering openings in the plates 22 and 23 and the block 21, and the rings 15 and 16, bearing against 90 the outer sides of the plates, materially assist in holding them and the block in place. A coupling 26 is secured against the concave side of the plate 23 by the bolts 24, and its lower portion is externally threaded and split 95 and receives a clamp nut or ring 27, by means of which the separated portions are drawn together and caused to grip the upper end of the brace 7.

The steering-head 28, to which the front 100 fork is attached, is expanded at its upper end and shaped to provide a cone 29, and a ring 30 has an inner flange providing a race to receive ball-bearings 31, which relieve the friction between the steering-head and the coupling 105 connecting it with the frame. A T-coupling 32, having its upper portion removed and internally roughened, is fitted to the front portion of the frame or at any other desirable point and has its intermediate portion split and externally threaded to receive the ring 30, by means of which the separated 110 parts are drawn together, so as to clamp the coupling to the frame-bar, the internally-roughened side preventing slipping when the 115 parts are in place. This coupling 32 is applied to the upper frame-bar. The lower frame-bar is split and spread to admit of the 120 passage therethrough of the steering-head 28, and a block 33 is fitted between the parts of the bar so separated, and plates 34 are secured to the top and bottom sides of the frame-bar opposite the block 33 and are retained in place by bolts 35 and fastenings 36, identical in construction with the fastening 125 comprising the parts 12 and 13. The plates 34 have offstanding collars to provide an extended bearing for the steering-head 28.

The strip, rod, or bar from which the frame is to be constructed is bent, forming the rear fork 20, the top reach 19, the lower reach 37, and the bottom run 38, whereby a frame of the ordinary diamond shape is provided, and the extremities of the blank or strip are se- 130

cured to the plate 1 in the manner set forth, thereby obviating any intermediate joints. The frame is strengthened and stayed by the upright or brace 7 in the usual manner, said brace being held in place by the means herein set forth.

The frame just described is especially designed for boys and men, and for misses and ladies the top reach is formed with a drop, as shown most clearly in Fig. 1 and at the front end of Fig. 3, the drop portion consisting of an upright 39 and a lower bar 40 about parallel with the lower reach 37. A Y-coupling 41 is located at the bend or juncture of the upper right 39 and the reach 40 and receives the upper end of the brace 8. In all other respects the frame illustrated in Fig. 1 is constructed substantially in the same manner as the frame shown in Fig. 2. The lady's seat-post 42 is notched in its front side, as shown at 43, and operates through a sleeve 44, secured to the upright 39 by clips 45 and is held in an adjusted position by a cam-lever 46, pivoted to the sleeve 44 and operating through an opening therein, as most clearly indicated in Fig. 14.

The handle-bar 47 is held in place by a clamp 48, which is secured to the steering-head by bolts or fastenings 49 in the usual manner. The upper portion of the clamp 48 is removable, as shown at 50, and its inner end has a lug or extension 51 to engage under a lip 52, and its front end is apertured to receive a machine screw or bolt 53, by means of which the parts of the clamp are brought together to secure the handle-bar 47 in an adjusted position.

For a combination tandem the frames illustrated in Figs. 1 and 2 are combined, as illustrated in Fig. 3, the top reach and bottom runs being extended to provide a frame of required length. A supplemental steering-head 54 is provided intermediate of the frame for the rear rider and is mounted in the coupling 32 in the manner set forth and in a bearing-sleeve 55, formed with the Y-coupling 41, and a rod 56 connects a lateral extension of the steering-head 54 with a corresponding extension of the steering-head 28, thereby causing the front and rear handle-bars to move in unison and in the same direction. The combination tandem illustrated in Fig. 3 is for a lady and gentleman, and when the machine is designed for men only the drop-frame will be dispensed with and the top reach extended and joined with the bar 37, as indicated in Fig. 2. The machine will be supplied with driving mechanism and supporting-wheels in the ordinary manner.

Having thus described the invention, what is claimed as new is—

1. A bicycle-frame constructed of a single looped strip of wood, having its end portions brought together at the lower end of the frame and split longitudinally to form corresponding right and left terminal elements, constituting a rear fork and rear braces, and hav-

ing its intermediate looped portion arranged to form a steering-head support, with the lower side of the loop split longitudinally, 70 and the portions bordering upon the split spread laterally to form separated intermediate elements, in combination with a block secured in the split between said intermediate elements, and provided with a steering-head 75 seat, means for securing said block in place, and means, forming axle-seats, for securing said terminal elements in operative relation, substantially as specified.

2. The herein-described bicycle-frame, consisting of a single looped length or strip of wood doubled upon itself to form a head-support and having the extremities of its upper and lower sides brought together at the lower rear end of the frame, and longitudinally split 85 to form corresponding right and left terminal elements constituting a rear fork and braces, rear-wheel-axle supports attached to said terminal elements and connecting the same in pairs to maintain them in operative 90 relation, a tubular brace transversely spanning the loop between the upper and lower sides thereof, and split longitudinally at its lower end to form separated elements, a crank-hanger secured to the lower side of the loop 95 and provided with means for engaging said brace elements, a block secured in the angle between the right and left terminal elements of the upper side of the loop and provided with an opening through which the upper end 100 of said brace extends, whereby the brace forms a seat-post tube, and a head mounted upon the looped strip adjacent to its front end, and between the sides of the loop, the lower side being split longitudinally to form 105 intermediate elements which are spread or bowed laterally, and a block being secured in the space between said intermediate elements, and provided with an opening through which the lower end of the head extends, sub- 110 substantially as specified.

3. In a bicycle, a bent-wood frame-bar bent upon itself to form a loop having upper and lower connected sides which are split longitudinally and spread or separated laterally at 115 their terminals and at an intermediate point, and head and seat post tubes transversely spanning the interval between the loop sides, and each extending through the interval formed by a split of one of said loop sides, a 120 block being fitted in each of the splits through which one of said tubes extends and having an opening in which the tube is fitted, substantially as specified.

4. In a bicycle, a bent-wood frame-bar split 125 longitudinally to form elements which are separated or spread laterally, an intersecting transverse frame member, a tapered block engaged with said intersecting frame member, and fitting snugly in the space between 130 the separated elements, a plate parallel with and covering the block and exceeding the same in area, to overlap and engage the separated elements of the frame-bar, and means

- encircling the bar at the extremities of the block and engaging the ends of the plate to hold said parts in fixed relations, substantially as specified.
5. In a bicycle or like machine, a bent-wood frame-bar having a split portion comprising laterally-spread elements, an intersecting transverse frame member, a tapered block engaged with the intersecting frame member, and fitted between said separated elements, upper and lower plates arranged parallel with and above and below the block, and exceeding the block in area to overlap and engage the separated elements of said frame-bar at the ends and sides of the block, and clamp-rings encircling the frame-bar at the ends of the block and engaging the extremities of the plates for securing said parts together, substantially as specified.
10. In a bicycle or like machine, the combination of a tapered plate provided with a shoulder and having its outer inclined face transversely toothed, a wooden frame-bar placed against said plate and shoulder, and a sleeve or cuff encircling the plate and frame-bar and having a transversely-toothed portion corresponding with the toothed portion of the plate and adapted to interlock therewith, substantially in the manner and for the purpose set forth.
15. In a bicycle or like machine, the combination of a plate having an outer inclined face which is toothed or roughened at a plurality of points in different planes, a wooden frame-bar in contact with said plate at the opposite side from its inclined face, and a sleeve or cuff having spaced portions of different diameters encircling the plate and frame-bar respectively in the planes of said toothed or roughened portions of the plate, and having roughened or toothed surfaces to interlock therewith, and secure the cuff or sleeve from longitudinal displacement, substantially as specified.
20. In a bicycle, a bent-wood frame, having a single looped strip, split longitudinally at its ends and spread laterally to form rear braces and a rear fork, with the elements of the former arranged respectively in common vertical planes with those of the latter and secured together, clamping-rings encircling the upper and lower sides of the looped strip at the points of divergence of said elements, a brace extending transversely of the looped strip and terminally arranged adjacent to the points of divergence of said elements, and means consisting respectively of a coupling and a crank-hanger engaged with the strip, at said points of divergence of its terminal elements, to secure the same against further splitting, and engaged with the extremities of said brace, substantially as specified.
25. In a bicycle or like machine, a frame-bar having a split portion comprising laterally-spread elements, a block fitted between said spread elements and constructed for engagement with an intersecting frame member, and fastening devices engaging the frame-bar to prevent further spreading of the elements and secure said block in place therebetween, substantially as specified.
30. In a bicycle or like machine, a frame-bar having a split portion forming laterally-spread elements, a block fitted between said elements and constructed for engagement with an intersecting frame member, plates arranged at opposite sides of said block and overlapping and engaging the spread elements of the frame-bar, fastening devices connecting the plate and block intermediate of their ends, and other fastening devices encircling the frame-bar adjacent to and engaging the extremities of said plates, substantially as specified.
35. In a bicycle or like machine, the combination with the frame, of a brace split longitudinally at its lower end to form separated divergent elements, a crank-hanger comprising a bearing-sleeve, upwardly-convergent extensions, arranged in contact with the inner sides of the elements of the brace, a collar, disposed between the said extensions, in a higher plane than the bearing-sleeve and at right angles thereto and adapted to have the lower frame-bar passed therethrough, and means for securing said vertical extensions to the elements of the brace, substantially as specified.
40. The herein-described crank-hanger for a bicycle or like machine, the same having an axially-transverse bearing-sleeve, upwardly-convergent extensions integral with the bearing-sleeve and in contact with the inner sides of the brace-bar elements, means for securing the said extensions to the said brace-bar elements, a split collar arranged in a plane above, said bearing-sleeve, and between said vertical extensions of the bearing-sleeve to receive a lower frame-bar, one element of said collar being integral with the bearing-sleeve, and clamp-rings having serrated inner faces for engaging serrated portions of the exterior surface of said extensions, to maintain the movable member thereof in operative relation with the fixed member, and in engagement with the lower frame-bar, substantially as specified.
45. In a bicycle or like machine, the combination with a wooden frame-bar, of a tapered plate having a shoulder to receive the end thrust of the bar, and integral projections on the same side to indent the surface of the bar, and a cuff or sleeve encircling and longitudinally movable independently of the plate and bar, for securing the same together, with the said projections in positive engagement with the frame-bar, said plate and cuff or sleeve having interlocking serrated faces to prevent accidental displacement of the latter, substantially as specified.
50. In a bicycle or like machine, the combination of a tapered plate provided with a shoulder and having its outer inclined face transversely toothed, a wooden frame-bar placed against said plate and shoulder, and a sleeve or cuff encircling the plate and frame-bar and having a transversely-toothed portion corresponding with the toothed portion of the plate and adapted to interlock therewith, substantially in the manner and for the purpose set forth.
55. In a bicycle or like machine, the combination of a plate having an outer inclined face which is toothed or roughened at a plurality of points in different planes, a wooden frame-bar in contact with said plate at the opposite side from its inclined face, and a sleeve or cuff having spaced portions of different diameters encircling the plate and frame-bar respectively in the planes of said toothed or roughened portions of the plate, and having roughened or toothed surfaces to interlock therewith, and secure the cuff or sleeve from longitudinal displacement, substantially as specified.
60. In a bicycle or like machine, the combination with the frame, of a brace split longitudinally at its lower end to form separated divergent elements, a crank-hanger comprising a bearing-sleeve, upwardly-convergent extensions, arranged in contact with the inner sides of the elements of the brace, a collar, disposed between the said extensions, in a higher plane than the bearing-sleeve and at right angles thereto and adapted to have the lower frame-bar passed therethrough, and means for securing said vertical extensions to the elements of the brace, substantially as specified.
65. In a bicycle or like machine, the combination with the frame comprising one-piece upper and lower frame-bars, of a steering head connecting the upper and the lower

frame-bars a short distance in the rear of the front end of the frame and passing centrally through the lower frame-bar which is split and spread to receive it, and a handle-bar secured to the steering-head at a point between the said upper and lower frame-bars, substantially as set forth.

15. In a bicycle or like machine, a frame comprising one-piece upper and lower bars, a steering-head passing centrally through the lower frame-bar which is split and spread to receive it, a coupling connecting the upper end of the steering-head with the upper frame-bar, and a handle-bar having connection with the steering-head at a point intermediate of the upper and lower frame-bars, substantially as set forth.

16. In a bicycle or like machine, the combination of a steering-head having a cone at its upper end, a T-coupling applied to an upper frame-bar and having one of its branches or portions split, a ring fitting the split portions thereof for connecting the steering-head with the coupling and causing the latter to grip the frame-bar, and constructed to provide a race, and ball-bearings operating in the race formed between the cone and the cup of the clamp-ring, substantially as set forth.

17. In a bicycle or like machine, the combination with the frame, a coupling secured to the upper side of the frame, and a brace having its upper end secured within the said coupling, of a seat-post tube passing through

an opening in the frame and entering a threaded bore formed in the upper end of the brace and secured therein and externally threaded, clamp-rings mounted upon the threaded portion of the seat-post tube above and below the frame, the lower ring engaging with and forming an abutment for the upper end of the brace and the upper ring serving to lock the seat-post tube in place, a seat-post, and means for securing the seat-post in its tube in an adjusted position, substantially as specified.

18. In a bicycle or like machine, a frame composed of a single strip or bar bent to provide an upright portion, upwardly and forwardly inclined reach-bars, and a bottom run, a separately-formed brace about in line with the upright portion of the frame, a substantially Y-shaped coupling located at the juncture of the upright and upper reach-bar portions of the frame and receiving the upper end of the brace, and a crank-hanger located at the juncture of the bottom run and reach-bar and receiving the lower end of the brace, substantially as set forth.

In testimony that I claim the foregoing as my own I have hereto affixed my signature in the presence of two witnesses.

JOHN WILLIAM PAYNE.
